BORIS B. HOPPE, OF KEW GARDENS, NEW YORK

FASTENING OR HOLDING DEVICE

Application filed August 17, 1929. Serial No. 386,627.

This invention relates to a device by means of which straps may be held in adjusted positions relative to each other. The device comprises two members, one of which is pivoted to the other with means to cause one of the members to clamp or grip a strap in one position and permit the strap to be released in another position.

The invention will be understood from the description in connection with the accompanying drawing, in which Fig. 1 is a perspective view of the device. Fig. 2 is a perspective view of a portion of a modification. Fig. 3 is a perspective view of another modification. Fig. 4 is a longitudinal section through the device shown in Fig. 3. Fig. 5 is a plan view of a sheet of metal from which one of the members is made, and Fig. 6 is a plan view of the other member.

In the drawing, reference character 1 indicates a bottom or base member of the device which is provided with a slot 2 near one end through which the end of a strap 3 can be introduced, and the end turned back and sewed or riveted or connected in any other convenient way to the main portion of the strap 3, thus securing the strap to the member 1. A curved lug 4 is connected to each side of the member 1 and extends upwardly with their upper ends provided with holes 5 to receive pivots of the other member of the device. The end of the member 1 opposite the slot 2 is curved to provide a groove 6 for an end of the other member of the device to snap into, as will be described below.

The other member of the device is pivoted to the member 1 and comprises an upper flat side 7, the front end of which is curved around, as indicated at 8, and provided with lugs or pivots 9 that extend into the holes 5 in the lugs 4 that are spaced sufficiently far apart to receive the side 7 between them. The upper side 7 of the member may be provided with a rectangular opening 10, the metal at one end of this opening being bent downwardly as indicated at 11, to provide a transverse stop or cross piece against which a strap may be pressed to grip the strap. The end of the side portion 7 opposite the curved end 8 is provided with a tongue or projection 12

which may be used for turning the member about the pivots 9.

The pivoted member is bent back, as indicated at 13, so as to provide two resilient portions or offset plate members spaced apart sufficiently to provide an opening 14 through which a strap 15 may be passed. The lower side 16 of the pivoted member extends back approximately the same distance as the upper side, leaving a space between the upper side 7 and the lower side 16 through which the strap 15 passes. The lower side 16 is bent at an angle to provide a shoulder 17 in proximity to the cross piece 11 for gripping the strap 15. The downwardly and the outwardly extending end of the side 16 is slightly curved, as shown at 18, to provide a rib that snaps into the groove 6 when the device is in the closed or gripping position.

When the upper or pivoted member is turned in the clockwise direction as shown in Fig. 1, with a strap 15 between the upper side 7 and the lower side 16, the free end of the lower side 16 slides along the top side of the member 1 between the lugs 4, thus pressing the shoulder 17 toward the cross piece 11 and tightly gripping the strap 15. The springiness of the metal of the pivoted member causes the free end of the side 16 to press against the member 1 and when the rib 18 snaps into the groove 6 the parts are securely kept in closed position. When the device is in the closed position, the rib or end 18 will have passed beyond what might be termed the dead center in a plane from the pivots 9 to groove 6, so that the spring in the metal will cause the end carrying the projection 12 to be pressed downwardly. The strap 15 can, however, be easily released, simply by pulling upwardly upon the projection 12 or even by pulling upwardly upon the free end of the strap 15, thus turning the pivoted member about the pivots 9 in anti-clockwise direction.

In the modification shown in Fig. 2, parts similar to those shown in Fig. 1 are designated by the same reference characters with the subscript 2. In this modification the base member 1₂ is made of U-shape from flat metal. The lugs 4₂ may be located along 100

the inner edges instead of the outer edges of the member. The free end of the lower side 16₂ of the pivoted member is bifurcated and lies flat against the top side of the member 1₂, as indicated at 18₂.

In the modification shown in Figs. 3 to 6, the lower or base member is shown as being made of wire, and the upper or pivoted member is shown as being stamped out from a flat metal sheet. The lower or base member is shown separately in Fig. 6 and consists of a piece of wire, the main portion 21 of which is bent into U-shape, with outwardly bent portions 22 and upstanding portions to provide pivots 23 for the pivoted member.

The pivoted member which may also be generally in U-shape, as already described for the pivoted member in Fig. 1, may be stamped out of a sheet of flat metal 24, as shown in Fig. 5. The sheet 24 is cut along parallel lines 26, along lines 27 at right angles to the lines 26, along parallel lines 28 closer together than the lines 26, along lines 29 at right angles to the lines 28, along parallel lines 30, and also transversely along a line 31 connecting the lines 30 near the ends thereof. The sheet 24 is also cut transversely along the line 32 and longitudinally along the ends of the line 32 a short distance.

The metal lying between the lines 26 to 31 is pushed downwardly and forwardly to the form shown in Figs. 3 and 4. A flat upper side 33 is left corresponding to the side 7 in Fig. 1, and a lower side 33' is left corresponding to the side 16 in this figure. A rectangular opening in the side 33 corresponding to the opening 10 is provided. The metal that was cut along the line 31 is bent downwardly to provide a cross piece 34 corresponding to the cross piece 11. A portion of the edges of the sheet 24 in the form of spaced members 35, connects the upper and lower sides 33 and 33' of the pivoted member and corresponds to the portions 13 in Fig. 1, when the pivoted member is formed with the spaced members 35 at an angle to the plate members 33 and 33'. The metal along the line 32 is bent upwardly to provide a shoulder or transverse gripping projection 36 in proximity to the cross piece 34.

The portion of the lower side 33' of the pivoted member beyond the projection 36 is bent downwardly and outwardly, as shown at 37, the groove 38 being provided to snap over the portions 22 of the base member in the gripping or holding position. In this modification, the strap 3 is shown as being held in place on the lower base member by means of the snap 3'.

The operation of the device, as is shown in Figs. 3 to 6, is similar to that already described.

I claim:

1. A fastening device comprising a member having upstanding portions, and a mem-

ber having offset plate members with free ends one of which is pivoted at its free end to the ends of said upstanding portions and the other of which bears at its free end against the body portion of said first named member.

2. A fastening device comprising a member having upstanding portions, a member having offset plate members one of which is pivoted to said upstanding portions and the other of which bears against said first named member, and is provided with a transverse extension for pressing a strap against the pivoted plate member.

3. A fastening device comprising a member having upstanding portions, and a member having resiliently connected offset plate members one of which is pivoted at its end to said upstanding portions and the other of which bears at its free end against the body portion of said first named member and extends longitudinally thereof sufficiently to cause said second-named member to be retained in its fastening position.

4. A fastening device comprising a member having upstanding portions, a member having offset plate members one of which is pivoted to said upstanding portions, and means to cause said offset plate members to grip an object between them when turned in one direction, said device also comprising a snap catch to retain said members in their gripping position.
